UNITED STATES PATENT OFFICE.

JOHN J. SWANSON, OF ELGIN, NEBRASKA.

TRANSMISSION-PEDAL CONTROL.

Application filed July 30, 1925. Serial No. 47,059.

To all whom it may concern:

Be it known that I, JOHN J. SWANSON, a citizen of the United States, residing at Elgin, in the county of Antelope and State of Nebraska, have invented certain new and useful Improvements in Transmission-Pedal Controls, of which the following is a specification, reference being had to the accompanying drawings.

10. This invention relates to transmission pedal controls and more particularly to the control of a low speed pedal of a planetary transmission.

15. An important object of the invention is to provide a device for holding this pedal in its low speed position so constructed that the pedal is firmly held in its operative position regardless of the wear upon the bands of the transmission, permitting changes in 20. the movement of the pedal.

25. A further object of the invention is to provide a device of this character which is semi-automatic in its operation, automatically releasing when its use is no longer desired by a slight pressure upon the pedal.

30. A still further object of the invention is to produce a device of this character which may be very cheaply produced and readily applied and which will be durable and efficient in service.

35. These and other objects I attain by the construction shown in the accompanying drawings, wherein for the purpose of illustration is shown a preferred embodiment of my invention and wherein:—

40. Figure 1 is a perspective view showing control apparatus constructed in accordance with my invention applied to the transmission of a well known type of vehicle;

45. Figure 2 is a perspective of the mechanism removed from the transmission;

Figure 3 is a perspective of the lock in the open position; and

50. Figure 4 is a perspective of the lock showing the same in closed position.

In the accompanying drawings, the numeral 10 generally designates the upper section of the case of a planetary transmission employed in a well known type of vehicle.

55. In the particular type of transmission case illustrated, the upper section of the case is provided centrally with a removable plate 11 held in position by securing elements, hereinafter to be more particularly referred to. To the left of this plate, the operating

pedals L, R and B are located controlling the constriction of the bands of the planetary transmission in the usual manner. These bands form no portion of my invention and accordingly have not been illustrated. The pedal L or low speed pedal is that with which the present invention is concerned is located at the extreme left, which pedal is moved forwardly to constrict the band associated therewith and as the band wears, the amount of movement of the pedal is accordingly increased. The transmission housing, in general, is supported by a band 12, the ends of which are arranged upon channel members 13 forming the side frames of the vehicle in which the transmission is employed and is secured to these channel members by bolts 14.

In accordance with my invention, I secure to the transmission case 10 preferably by means of certain of the securing elements 15 of the removable plate 11 a bracket 16, the forward end of which is downwardly and forwardly inclined, as at 17. To the bracket 16 immediately rearwardly of this 20 forwardly and downwardly inclined portion, I secure one end of a transverse bar 18, as indicated at 19, the opposite end of this transverse bar being held in position by the bolt 14 securing the left hand end of the strap 12 to its associated channel element.

Pivotal secured to this bar adjacent the left hand end thereof and as at 20 is the stem 21 of a hook 22; the inner face 23 of which is substantially spirally arranged as regards the pivot 20, and is formed with a series of notches 24 designed to receive the front face of the pedal lever. The portion of the bar 18 upon which the hook is arranged is so positioned that the hook is disposed at substantially right angles to the engaged portion of the pedal when in its operative position, it being necessary to bend the bar, as indicated at 25, to provide for this. Pivotal secured to the down-bent 100 end 17 of the bracket 16, as at 26, is the lower end of a hand lever 27 to which is pivotally connected one end of a link 28, the opposite end of which is rotatably engaged in an opening 29 formed in the hook. This 105 hand lever is further connected by a tension spring 30 with a securing bolt 15 of the cover plate 11 arranged to the left of the lever so that this lever tends to move at all times toward the hook and accordingly 110

to swing the hook which is arranged at the left hand side of the pedal L away from the pedal.

In the use of the device, the pedal L is forced forwardly by the foot to its greatest possible extent and the hand lever 27 is then moved in the direction of the arrow A of Figure 1. This causes the hook to be engaged with the lever L and prevent its return movement, thus holding the band associated with the lever in its operative position. The point of engagement of the lever with the hook will be determined by the condition of this band. If the band be but newly applied, the point of engagement will be at the outer end of the lever but after the band becomes worn, the engagement will be further and further away from said outer end. This hook, when in applied position, will serve to hold the low-speed pedal in its operative position without the necessity of the driver's placing his foot thereon, thus relieving the driver considerably when the machine is operating under heavy loads, ascending high hills or moving in the face of a high wind. When it is desired to release the pedal, all that is necessary is the application of pressure to the pedal, tending to force the same forwardly and releasing the pedal from its engaged notch. As soon as this notch is released, the spring 30 will act to move the hand lever 27 in the direction opposite to that of the arrow A, causing the hook to be disengaged and the pedal released for its normal operation.

Since the construction hereinbefore set forth is obviously capable of a certain range of change and modification without materially departing from the spirit of my invention, I do not limit myself to such specific structure except as hereinafter claimed.

I claim:

1. In combination with a transmission including a pedal oscillatable in a vertical plane, the oscillation of the pedal to one extreme of its movement being variable, a spring tending to return the pedal from the last named position, a latch pivotally supported from the transmission housing to swing in a horizontal plane, said latch having a pedal engaging face provided with notches for the reception of the pedal, said pedal engaging face being spirally disposed to the pivot of the latch, means likewise supported from the transmission casing oscillatable in a substantially vertical plane at right angles to the plane of movement of the pedal for shifting said latch into pedal engaging position and a spring operatively engaged with the latch for moving the latch to position where the pedal is released.

2. In combination with a transmission including a pedal oscillatable in a vertical plane, the oscillation of the pedal to one

extreme of its movement being variable, a spring tending to return the pedal from the last named position, a latch pivotally supported from the transmission housing to swing in a horizontal plane, said latch having a pedal engaging face provided with notches for the reception of the pedal, said pedal engaging face being spirally disposed to the pivot of the latch, means likewise supported from the transmission casing oscillatable in a substantially vertical plane at right angles to the plane of movement of the pedal for shifting said latch into pedal engaging position.

3. In combination with a transmission including a pedal oscillatable in a vertical plane, said transmission having supports and a housing including a removable plate and securing elements for said plate, a bar held in position upon the transmission by said securing elements and extending longitudinally of the transmission, a second bar secured to one end of the first named bar and its opposite end to one of said supports, said bar extending adjacent said pedal, a horizontally swingable hook pivoted to the bar and having a spirally curved pedal engaging face provided with notches, a pivoted lever carried by the first named bar and a link connection between said hook and lever for moving the hook into engagement with the pedal.

4. In combination with a transmission including a pedal oscillatable in a vertical plane, said transmission having supports and a housing including a removable plate and securing elements for said plate, a bar held in position upon the transmission by said securing elements and extending longitudinally of the transmission, a second bar secured to one end of the first named bar and its opposite end to one of said supports, said bar extending adjacent said pedal, a horizontally swingable hook pivoted to the bar and having a spirally curved pedal engaging face provided with notches, a pivoted lever carried by the first named bar, a link connection between said hook and lever for moving the hook into engagement with the pedal and a spring engaged with said lever and constantly urging the same in a direction to release said hook.

5. In combination with a transmission including a pedal oscillatable in a vertical plane, said transmission having supports and a housing including a removable plate and securing elements for said plate, a bar held in position upon the transmission by said securing elements and extending longitudinally of the transmission, a second bar secured to one end of the first named bar and its opposite end to one of said supports, said bar extending adjacent said pedal, a horizontally swingable hook pivoted to the bar and having a spirally curved

pedal engaging face provided with notches, a pivoted lever carried by the first named bar, a link connection between said hook and lever for moving the hook into engagement with the pedal and a spring engaged with said lever and constantly urging the same in a direction to release said hook se-

cured at one end to the lever and at its opposite end to one of the securing elements of said removable plate. 10

In testimony whereof I hereunto affix my signature.

JOHN J. SWANSON.
